UNITED STATES PATENT OFFICE.

MORRIS P. KATZANDER, OF PHILADELPHIA, PENNSYLVANIA.

CHAIR CONSTRUCTION.

Application filed August 21, 1928. Serial No. 301,091.

The invention relates to a chair construction.

The object of the present invention is to provide a simple, practical and comparatively inexpensive easy chair adapted to be readily arranged to form a couch.

A further object of the invention is to provide a combined easy chair and folding couch of this character provided with a hinged back 10 which may be lowered into a horizontal position to form one end of the couch and provided with a hinged arm frame capable of being swung forwardly and downwardly in advance of the base frame of the chair to 15 form the front section of the couch.

Another object of the invention is to provide a combined easy chair and couch in which the upholstery of the back will take the place of a rear section of a mattress and it will be 20 necessary only to provide a mattress of two sections to fit the arm frame and the base frame when the chair is unfolded to form a couch.

Another object of the invention is to construct the base frame, the hinged back and the hinged arm frame so that when the chair is unfolded to form a couch the parts will abut compactly together and the upper face of the lower back will be arranged in substantially the same plane as the upper edges 25 of the base frame and the arm frame.

With these and other objects in view, the invention consists in the construction and novel combination and arrangement of parts 30 hereinafter described, illustrated in the accompanying drawings, and set forth in the claims appended hereto, it being understood that various changes in the form, size, and minor details of construction, within the scope of 35 the claims, may be resorted to without departing from the spirit of the invention or sacrificing any of the advantages thereof.

In the drawings:

Figure 1 is a plan view of a combined easy 45 chair and couch constructed in accordance with this invention, the parts being arranged to form a couch.

Fig. 2 is a longitudinal sectional view of the combined easy chair and couch showing 50 in full lines the arrangement of the parts to form an easy chair and in dotted lines to form a couch.

Fig. 3 is a transverse sectional view taken 55 substantially on the line 3-3 of Fig. 2.

Fig. 4 is a detail perspective view of the hinged arm frame.

Fig. 5 is a detail perspective view illustrating the construction of one of the rear corners of the chair.

Fig. 6 is a plan view of the mattress.

60

Fig. 7 is a side view of the same.

In the accompanying drawing in which is illustrated the preferred embodiment of the invention the combined easy chair and couch comprises in its construction a base frame 1,

65

a hinged back 2 and a hinged arm frame 3, the back being adapted to swing downwardly from an upright position shown in full lines in Fig. 2 of the drawing to the dot and dash line position in said figure and the arm frame 70

3 being adapted to swing forwardly and downwardly to the dot and dash line position in Fig. 2 to convert the easy chair into a couch.

75

The base frame 1 which is substantially rectangular is composed of sides 4, front and rear connecting cross pieces 5 and 6 and front and rear legs 7 and 8. The cross pieces 5 and 6 are composed of pieces of a width less than the pieces which form the sides of the base frame and the upper edges of the 80

front and rear cross pieces terminate short of the upper edges of the sides 4 to form front and rear transverse recesses 9 and 10. The front recess 9 provides a space for the accommodation of a mattress 11 when the parts of 85

the easy chair are arranged to form a couch and the rear recess 10 provides a space to receive the hinged back of the chair when the said back is swung downwardly to the dot and dash line position illustrated in Fig. 2.

90

The rear legs 8 are provided at their upper ends with a recess 12 located at the rear faces of the legs 8 and forming corner recesses to cooperate with the lower corner recesses 13

of the sides 14 of the hinged back and the 95 recessed portions of the legs 8 and the sides 14 of the hinged back interfit when the back of the chair is swung downwardly to form a couch.

The back of the chair is composed of the 100 said sides and upper and lower connecting cross pieces 15 and 16, the open space 17 shown in the drawings and defined by the upper and

lower cross pieces and the sides of the hinged back being adapted to receive any suitable 105 upholstery which in practice will form one section of the cushion of the couch when the back of the chair is swung downwardly to the dot and dash line position in Fig. 2 of the

drawings. When the back is swung down- 110 wardly its upper upholstered face is substantially in flush relation with the plane of the

as to extend below the upper edges of the cross pieces of the main frame to provide a mattress or cushion receiving space, and a substantially U-shaped arm frame arranged upon the base frame and composed of spaced sides and a rear connecting bar arranged at the bottom of the sides of the arm frame, the front of the U-shaped frame being open to provide an entirely open cushion or mattress receiving space above the front cross bar of the main frame when the chair is folded, the said arm frame being hinged at the front ends of the sides to the base frame and adapted to swing downwardly and forwardly in advance of the base frame to form a front section.

3. A foldable chair construction comprising a base frame, a back pivoted to the base

frame, another frame pivoted on the base frame at the front of the latter, said other frame having posts each having an inclined edge and arranged to form rigid supporting legs when said other frame is swung downwardly in advance of the base frame to support said other frame in horizontal relation with the base frame, said posts presenting their inclined edges to the back frame in parallelism with the back frame and relatively close thereto to provide a substantially closed compact corner structure for the chair when the latter is folded.

In testimony whereof I have hereunto set my hand this 25th day of July, 1928.

MORRIS P. KATZANDER.
